Primary Examiner — Marie D. Fast Horse

(57) **CLAIM**

The ornamental design for a remote control, substantially as shown and described.

DESCRIPTION

FIG. 1 is a top perspective view of a remote control as seen from the bottom, front, and right side;

FIG. 2 is a top view thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.

The broken line shown in the drawings depicts a portion of the remote control that forms no part of the claimed design.

1 Claim, 3 Drawing Sheets
